CLAIM

The ornamental design for a screwdriver handle, as shown and described.

DESCRIPTION

FIG. 1 is an elevational view of a screwdriver handle

showing my new design with a screwdriver blade being shown in broken line, and in which the stippling represents a portion of a color or tone different from that of the unstippled portion; the same view is presented if the screwdriver handle is rotated about its longitudinal axis through 120° and through 240°;

FIG. 2 is an elevational view of the screwdriver handle rotated 180° about its longitudinal axis from the position of FIG. 1; the same view is presented if the screwdriver handle is further rotated about its longitudinal axis through 120° and through 240°;

FIG. 3 is an elevational view of the screwdriver rotated 90° about its longitudinal axis from the position of FIG. 2; the same view is presented if the handle is further rotated about its longitudinal axis through 120° and through 240°;

FIG. 4 is a top view of the upper end of the screwdriver handle as seen in FIGS. 1 and 2;

FIG. 5 is a cross sectional view along the line 5—5 of FIG. 1;

FIG. 6 is a cross sectional view along the line 6—6 of FIG. 1;

FIG. 7 is a cross sectional view along the line 7—7 of FIG. 1;

FIG. 8 is a view similar to FIG. 2 of another embodiment of the screwdriver handle having the same shape as the preceding Figures, but having top and bottom portions which are transparent; and

FIG. 9 is a cross sectional view along the line 9—9 of FIG. 4; and,

FIG. 10 is a bottom plan view of the handle of FIG. 1.

The broken line showing of the screwdriver blade is for illustrative purposes only and forms no part of the claimed design.
